INVENTOR

BY Victor J. Evans.

ATTORNEY

J. A. Hoy,
L. B. Middleton.

WITNESSES:

UNITED STATES PATENT OFFICE.

TEODOR NADOLNY, OF ELIZABETH, NEW JERSEY.

LOCK.

1,411,123.

Specification of Letters Patent. Patented Mar. 28, 1922.

Application filed June 14, 1921. Serial No. 477,607.

To all whom it may concern:

Be it known that I, TEODOR NADOLNY, citizen of Republic of Poland, residing at Elizabeth, in the county of Union and State of New Jersey, have invented new and useful Improvements in Locks, of which the following is a specification.

This invention relates to a lock of the type wherein a number of movable elements must be arranged in a certain relation to permit the shackle to be withdrawn to unlocking position, the general object of the invention being to provide a plurality of reversible ring members each having two sets of indication marks thereon so that new combinations can be provided by reversing the ring and by interchanging them.

Another object of the invention is to provide a slidable member for locking the other limb of the shackle.

A still further object of the invention is to provide means for holding the rings in place with spring pressed locking means for such means which are held in locked position by the shackle when the same is in closed position.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation of a lock constructed in accordance with my invention.

Figure 2 is a longitudinal sectional view through the lock.

Figure 3 is a section on line 3—3 of Figure 2.

Figure 4 is a section on line 4—4 of Figure 2.

Figure 5 is a view of one of the ring members.

Figure 6 is a view similar to Figure 2 but showing the parts in unlocked position.

Figures 7 and 8 are detail views.

In these views 1 indicates the lock casing which is provided with an extension 2. This casing is provided with the holes 3 and 4, for receiving the ends of the shackle 5, the hole 4 extending through one side of the extension

2 where it takes the form of a semi-circular groove 4'. One limb of the shackle is provided with an extension 5' for engaging this groove and this extension is provided with notches 5". The four ring members 6 fit over the extension and are held in place by the member 7, the stem 8 of which passes through a hole 9 in the extension with the head 10 engaging the end of the extension. 65 This head is of practically the same diameter as the rings and carries a pair of pins 11 which engage holes 12 in the stem. These pins act to properly position the member on the extension. Each ring is formed 70 with a central collar 13 which is knurled so that the ring can be easily rotated by the thumb and finger and a set of indication marks and numerals 14 are placed on the ring at each side of the collar. Only one 75 set of marks is used at a time but by reversing one or more rings or rearranging the rings new combinations can be secured. Each ring is also provided with an interior flange 15 for engaging the notches 5" in the 80 shackle and each flange is interrupted, as at 16, for disengaging the shackle from the flange. It will be understood that when all the rings are arranged with the spaces 16 registering with each other and with the 85 notched part of the shackle, said shackle can be withdrawn without interference upon the part of the rings.

The member 7 is held in position by means of a pin 17 engaging notch 18 in the inner 90 end of the stem 8 of said member, this pin being slidably mounted in a transverse hole 19 in the lock case. A spring 20 tends to force the pin out of the notch but said pin is held in engagement with the notch by 95 the beveled end 21 and the short limb of the shackle engaging the head of the pin when the shackle is in closed position. When the shackle is in open position the spring will force the pin out of the notch 100 so that the member 7 can be withdrawn. Said member 7 must be forcibly withdrawn from the device as it is frictionally held therein when the pin is in inoperative position. The short limb of the shackle 105 is provided with a notch 22 which is arranged adjacent the beveled end 21 and a laterally sliding bolt 23 has a part held in engagement with said notch 22 by the spring plunger 24 located in a transverse opening 110 25 in the lock case. This bolt 23 passes through a laterally arranged slot 26 in the

case which is arranged at right angles to the opening 25 and this slot 26 passes through the sides of the casing with the ends of the bolt projecting from the casing 5 where they receive the knurled heads 27. The plunger 24 has its head engaging the long limb of the shackle and when the shackle is withdrawn from the lock case to a certain extent this head will enter an annular groove 28 immediately above the notch part of the shackle to prevent further withdrawal of the shackle. However, in this position the short end of the shackle will clear the top of the case so that the shackle can 10 be turned to permit it to engage or be disengaged from the part to be locked. An arrow 29 is placed at the lower part of the lock casing for indicating the setting points of the two upper rings and a similar arrow 15 30 is placed on the head 10 of member 7 to indicate the setting points of the lower rings.

To unlock the device the rings are turned to bring the proper combination marks opposite the arrows 29 and 30 so as to place 25 the spaces 16 of the rings over the notched part of the shackle. Bolt 23 is then moved inwardly by pressing upon the heads 27 so as to move said bolt out of engagement with notch 22. The shackle will then be free to 30 move outwardly but when groove 28 comes opposite the plunger 24 the spring of said plunger will force the head thereof into said groove and thus prevent further withdrawal of the shackle. The shackle is then 35 turned to free it from or engage it with the part to be locked. When the shackle is in unlocked position the member 7 can be withdrawn to change the combination by reversing or interchanging the rings on the 40 extension 2. When the shackle is pushed in the bolt 23 will be forced into the notch 22 by the spring plunger so as to hold the shackle in closed position and then if it is desired to prevent an unauthorized person 45 from opening the lock it is simply necessary to rotate the rings to place the flanges into engagement with the notches 5". When the shackle is pushed in, its beveled end engaging pin 17 will force the end of said pin in- 50 to engagement with the notch 18 of the member 7 to lock said member and the rings in position. One side of the shackle adjacent the groove 28 is beveled, as at 28', to permit the spring plunger to move out of the groove 55 when the shackle is pushed inwardly.

It is thought from the foregoing description that the advantages and novel features of my invention will be readily apparent.

I desire it to be understood that I may 60 make changes in the construction and in the combination and arrangement of the several parts, provided that such changes fall within the scope of the appended claims.

What I claim is:—

65 1. A lock of the class described compris-

ing a case having an extension, said extension having a groove therein, a shackle passing through the case and having a notched part engaging the groove, rotatable ring members on the extension having interrupted flanges for engaging the notches in the shackle, indication marks on said rings and a part of the casing for setting the rings, and a slideable member in the main casing and engaging a notch in the shackle. 70 75

2. A lock of the class described comprising a case having an extension, said extension having a groove therein, a shackle passing through the case and having a notched part engaging the groove, rotatable ring 80 members on the extension having interrupted flanges for engaging the notches in the shackle, indication marks on said rings and a part of the casing for setting the rings, a slideable member carried by the cas- 85 ing and engaging a notch in the shackle and means for locking the rings on the extension when the shackle is in closed position.

3. A lock of the class described comprising a case having a grooved extension, a shackle having a notched extension at one end for engaging the groove, flanged ring members rotatably mounted on the extension and having their flanges arranged to 95 engage the notches in the shackle, said flanges having openings therein, each ring member having two sets of indication marks thereon, a locking member passing through the extension and having a head for holding the rings on the extension, a locking pin for said member and means for moving the pin into locking position by the shackle 100 when the same is in closed position.

4. A lock of the class described comprising 105 a casing having a grooved extension, a shackle having a notched extension at one end for engaging the groove and a notch adjacent its other end, a slideable member passing through the case and arranged to 110 engage said notch, the long limb of the shackle having a groove therein at the point of junction of the extension with the shackle, a spring plunger engaging the sliding member and having a part adapted to engage 115 the groove when the shackle is partly withdrawn, a plurality of ring members rotatably mounted on the extension of the case and having interrupted flanges for engaging the notches in the extension of the shackle and means for holding said rings 120 in position.

5. A lock of the class described comprising 125 a casing having a grooved extension, a shackle having a notched extension at one end for engaging the groove, and a notch adjacent its other end, a slideable member passing through the case and arranged to engage 130 said notch, the long limb of the shackle having a groove therein at the point of junc-

tion of the extension with the shackle, a spring plunger engaging the sliding member and having a part adapted to engage the groove when the shackle is partly withdrawn, a plurality of ring members rotatably mounted on the extension of the case and having interrupted flanges for engaging the notches in the extension of the shackle and means for holding said rings in

position, said means consisting of a member 10 having a stem and a head and a pair of pins projecting from the head, the case extension having openings for receiving the stem and pins and a spring pressed pin for holding said member in locked position 15 when the shackle is in closed position.

In testimony whereof I affix my signature.
TEODOR NADOLNY.
